UNITED STATES PATENT OFFICE.

EMIL A. STRAUSS, OF CHICAGO, ILLINOIS.

BOLTWORK MECHANISM FOR SAFE AND VAULT DOORS.

No. 869,992.

Specification of Letters Patent.

Patented Nov. 5, 1907.

Application filed April 22, 1907. Serial No. 369,472.

To all whom it may concern:

Be it known that I, EMIL A. STRAUSS, a citizen of the United States, residing in Chicago, Cook county, Illinois, have invented certain new and useful improvements 5 in boltwork mechanism for safe and vault doors and like devices and means for retaining said bolts in their locked position; and I hereby declare the following to be a full and correct specification thereof, reference being had to the hereto accompanying drawing, 10 forming a part hereof, and in which—

Figure 1 shows a construction of my said device in elevation as seen on the inside of a circular door, though applicable to any form of door. Fig. 2 shows a horizontal section taken on the plane x x cutting parts 15 and leaving the pitman-rods and minor other parts entire, and readily understood from the drawings.

Like reference letters denote like parts throughout.

My said new construction is made, substantially, as follows, namely: On a fixed ring b rides and turns a master gear-wheel a provided on its external and entire circumference with gear teeth a' , and a series of slots a^2 in which play studs c provided with anti-friction rings d , said slots a^2 having, in this specific construction, a length 25 equal to half the circumference of the gear-wheels, or 20 pinions, e . To each of said pinions is attached, fixedly, an eccentric e' which is embraced by the inner end of a pitman-rod f having its other end held to the locking-bolt g by a pin f' . Said pinions e turn on studs c^2 and 30 are actuated by means of a rack-bar h which receives its motion from a gear-wheel i on a shaft i' passing to the outside of the door, and where it is provided with any suitable actuating device, as a hand-lever i^2 . Said gear-wheel i is lengthened so as to engage the rack j on 35 one edge of the rack-bar h , and on the opposite edge and opposite end of said rack-bar is a rack k which engages with a pinion e^3 which is also made longer, as shown, so as to reach said rack-bar, and the object of said rack-bar is simply for the purpose of reducing friction and easing the action of the mechanism in moving said master-wheel a with its many bolts g , one to every fifteen

degrees of the circle, as shown in this case. The said mechanism could, however, be actuated directly from the wheel i which also meshes with the pinion e next to it, as clearly seen on the right hand end of both drawings, or, from any one of said gear-wheels e .

The master-wheel a engages with every pinion e of the series and as each pinion e turns and carries the eccentric e' with it the bolt g is shot outward until the half revolution of the wheel e is completed and by that time the motion of the rack-bar exhausted, thus causing each bolt to be held on the "dead center" of its said actuating mechanism, which is an important point in the position of such locking mechanism because no force applied to such bolt can give any motion to said mechanism.

What I claim is:

1. The combination with reciprocable locking-bolts and pitman-rods connected thereto, of a rotatable gear-wheel, pinions to engage said wheel, and means to reciprocably connect said pinions and pitman-rods.
2. The combination with reciprocable locking-bolts and pitman rods connected thereto, of a master gear-wheel and gear-wheels and means to rotate said wheels and to actuate said bolts.
3. The combination with a master gear-wheel, pinions engaging therewith, pitman-rods connected to said pinions and means to actuate said parts, of reciprocable bolts connected to said rods.
4. The combination with a master gear-wheel, pinions engaging therewith, pitman rods connected to said pinions, and means to actuate said rods and to hold them at the dead center, of reciprocable bolts connected to said rods.
5. The combination with reciprocable locking-bolts, of a master gear-wheel, pinions engaging therewith, eccentrics thereon and means to reciprocably connect said bolts and eccentrics.
6. The combination with locking-bolts and a reciprocable rack, of pinions eccentrics secured to said pinions pitman-rods to connect said bolts and eccentrics, and means to reciprocate said rack.

EMIL A. STRAUSS.
